CLAIM

The ornamental design for swimming goggles, as shown and described.

DESCRIPTION

FIG. 1 is a front perspective view of swimming goggles, showing my new design;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines in the figures illustrate portions of the swimming goggles that form no part of the claimed design.
